UNITED STATES PATENT OFFICE

HOWARD L. KRUM AND JOHN O. CARR, OF CHICAGO, ILLINOIS, ASSIGNEES, BY MESNE ASSIGNMENTS, TO TELETYPE CORPORATION, OF CHICAGO, ILLINOIS, A CORPORATION OF DELAWARE

TELEGRAPH SYSTEM

Application filed August 23, 1922, Serial No. 583,718. Renewed May 11, 1928.

Our invention relates generally to telegraph systems, and more particularly to printing telegraph and like systems wherein synchronously operated transmitting and receiving distributor are employed.

One object of our invention is to provide novel means for controlling the electric motors which drive the distributor. In prior systems a control of the motor has been obtained by varying the load, or by varying the circuit of the armature or field of the motor, or both. In many of these prior systems, much time is required to get the systems into operation. By our arrangement the motor is supplied with both alternating current and direct current, and when it has been brought up to speed by the direct current, it operates in some respects at least as a synchronous motor. With our arrangement we are able to place the system in operating condition in a very short time.

Another object of our invention is to provide the vibrating member by which the alternating current is supplied to the motor of the corrected distributor, with a new control. For this purpose we employ two electromagnets, one of which is energized intermittently, and the other of which is energized by continuous but varying current. There are novel features in the joint operation of these controlling elements and in their sole operation in combination with other parts of the system.

Another object of our invention is to provide a novel adjustment of the receiving distributor contacts so that the operating contact associated with the signal receiving contacts and corresponding to the operating impulse which follows the signal impulses, bears a constant and unchanging relation to the signal receiving contacts, and yet an adjustment is had by which the latter receive the incoming impulses most efficiently. This result is preferably obtained by adjusting the receiver correcting contacts, as a whole, relative to the other contacts of the receiving distributor.

A further object of our invention is to provide novel indicating means for making

known the relative speeds of the correcting and corrected distributor. In its specific embodiment signal lamps are connected to special indicator contacts on the head of the corrected distributor and the associated traveling means, whether a brush or contacts otherwise operated, applies impulses received from the correcting distributor in such a way that the operation of the lamps shows which distributor is traveling the faster and how much faster. Novelty resides in the indicating means itself and in its combination with other parts of the system.

A still further object of our invention is to so arrange the parts of the system that the normal current on the line when running idle, that is, when sending blank signals, will give frequent polarity reversals for correction purposes and so that a modification of the same normal current may be used in operating the indicating means. To this end we preferably normally send a pure alternating current to line. Its reversals of polarity assure frequent corrections, and by switching out every other wave a pulsating current of regular frequency is obtained for indicating purposes.

The above and other objects and features of our invention will be more fully understood upon reference to the following detailed description taken in connection with the accompanying drawing, wherein we disclose a preferred embodiment of our invention, while the scope of our invention will be particularly set forth in the appended claims.

In said drawing:

Fig. 1, consisting of parts 1 and 2, is a diagram of a printing telegraph system constructed and arranged in accordance with the present invention.

Fig. 2 is a face view of the contact head and casing of the receiving distributor.

Fig. 3 is a side elevation of the same.

Fig. 4 is a sectional detail view showing particularly how the correcting segments may be adjusted with reference to other segments of the head.

Fig. 5 is a view, illustrating in diagram

seven stages or conditions of the indicator lamps and their associated distributor contacts, arranged to illustrate how the lamps indicate the relative speeds of the correcting and corrected distributor.

5 Fig. 6 is a side view of a portion of the tuning fork used in the control of the motor which drives the receiving distributor, in association with magnets which control its movements; and

10 Fig. 7 is a plan view of the same.

Throughout these views, like characters refer to like parts.

Referring to the drawing in detail, A designates the bank of transmitter contacts which are operated in various code combinations in accordance with the signal to be transmitted; B the developed segmental contacts of the transmitting distributor head and their associated brushes; C the motor by which the transmitting distributor is driven; D the mechanism for controlling the application of alternating current to motor C; E the bank of receiving relays; F the developed segmental passive contacts of the receiving distributor; G the motor for driving the receiving distributor; H the mechanism for controlling the application of alternating current to the motor G; I the motor driven rheostat which controls the current flow through one of the windings of the motor control mechanism H; and J a series of associated relays which includes the line relay LR, the printing relay PR, the switching relay SR, the correcting relay CR, the motor relay MR, and the holding relay HR. These various parts constitute the equipment at each station upon the line L. In the diagram the latter is shown by a broken line to indicate that it extends to a station at a distant point. The only equipment of the second station which is shown is the line relay LR' and some of its connections, but it is to be understood that the other parts mentioned are to be found at the distant station also.

For the purpose of illustrating our invention, we have shown a system intended for use with the Baudot code, although it will be understood that the same may be modified to meet the requirements of other similar codes. According to the Baudot code, there are five current impulses or signal intervals for each character or signal, and each set of five impulses is followed by a single impulse, not necessarily sent over the line, for performing some additional function such as operating the printer magnet. At this point it may be well to mention also that the invention is shown in a system employing a line. It will be obvious from the present description, however, that the invention is applicable also to wireless systems wherein current waves are transmitted through the air, or ether, or other agency

than a telegraph wire. In such case the line conductors would give place to aerial conductors. It will also be apparent that many of the features of the invention will be applicable in wholly different environments than herein set forth.

We may now consider the contact bank A and the contacts of the associated transmitting distributor B. The transmitter contact bank A, being designed for the Baudot code, includes a set of five contacts 10. These contacts are supplied with current from supply mains 11 and 12 through leads 13 and 14 controlled by a switch 15. When the switch 15 is closed, the first, third and fifth contacts 10 are connected to the positive main 11, and the intermediate contacts 10, viz: the second and fourth, are connected to the negative main 12. When moved to their alternate positions, the first, third and fifth contacts 10 are connected to the negative main 12, and the second and fourth are connected to the positive main 11. With this arrangement it will be seen that the marking impulses of the first, third and fifth contacts 10 are negative, and the marking impulses of the second and fourth contacts 10 are positive. The set of contacts 10 are permanently connected by a series of conductors 16 to five segmental transmitting contacts 17 forming part of the transmitter distributor head. These connections are such that when the brush 18 passes over the contacts 17 they successfully bring the contacts 10 into circuit and apply either positive or negative current to the transmitting ring 19 and the connected conductor 20. In the present instance the system is arranged for two channel work and, therefore, the segmental contacts 17 are duplicated in the contacts 17', and the conductors 16 are duplicated in the conductors 16'. In the case of the transmitting contacts of the second channel, we employ the same arrangement as in the case of the first channel but interchange the connections to the supply mains 11 and 12. In other words, whereas in the first channel, lead 13 is connected to main 11, we connect the lead 13' of the second channel through switch 15' to the negative main 12. Similarly, whereas in the first channel, lead 14 is connected to the negative main 12, we connect the lead 14' of the second channel to the positive main 11. As a result of this arrangement, a pure alternating current is supplied to the conductor 20 whenever the transmitter is allowed to run idle with the switches 15 and 15' closed. This means that as the brush 18 passes over the contacts 17 and 17' the current impulses passing through the first channel will be successively positive, negative, positive, negative, positive, and that the current impulses immediately following through the 130

second channel will be successively negative, positive, negative, positive, negative. Thus a pure alternating current is supplied to the line as long as the transmitting distributor continues to run idle. Besides the transmitting segmental contacts 17, 17', and ring contact 19, with their associated brush 18, there are the local segmental contacts 21 and 21' co-operating with a ring contact 22 by means of brush 23 to close a circuit through the transmitter operating magnet 24, the circuit being completed from battery 25. Whenever the brush 23 engages contact 21, the magnet 24 will be operated to perform some function in connection with the transmitter, such as releasing the actuated keys of a keyboard transmitter, in case such is employed, or to cause the advance of the tape, in case a tape transmitter is employed. It will be understood that the contacts 10 may be operated in either of these ways, such mechanism being common and well known in the art. The segmental contact 21 is positioned so as to close its circuit just after the circuit has been closed through the last of the transmitter contacts 10. Thus in transmitting, the five current impulses applied to the conductor 20 are followed by a local impulse through the magnet 24. Just as the local magnet 21 is associated with the transmitting contacts 17 of the first channel, so the local contact 21' is associated with the transmitting contacts 17' of the second channel, and controls a magnet similar to the magnet 24.

We may now consider the motor C and its controlling mechanism D. The motor C is provided with a field winding 25 which is connected by leads 26 and 27 through switch 28 to the supply mains 11 and 12. A path, in parallel to the field winding 25, extends from lead 27 through the commutator 29 the direct current winding of the motor armature and back through the commutator 29 to one terminal of the resistance 30 of the rheostat 31, the arm 32 of which is connected to the lead 26. The winding of motor armature is also provided with alternating current taps or, if desired, an additional alternating current winding connected to the collecting rings 33 and 34, and the latter are included in circuit by means of conductors 35 and 36 with the terminals of a secondary winding 37 of a transformer 38. A lamp 39 is included in this circuit. The primary windings 40 and 41 of this transformer are connected at an intermediate point to ground and at their remote terminals to conductors 42 and 43, respectively. The latter terminate in contacts which co-operate with a vibrating contact 44 mounted upon one arm of the fork 45 of the control mechanism D. The fork 45 is mounted on a suitable base so as to leave its fixed end is connected in circuit with a battery 46. As the fork 45 vibrates, the contact 44 connects alternately with conductors 42 and 43 and thereby supplies a current, first, through winding 40 in one direction, and then through winding 41 in the opposite direction. These alternate applications of current in opposite directions induce an alternating current in the secondary winding 37 which is applied through the rings 75 33 and 34 to the alternating current winding of the armature of motor C. The fork 45 is provided with adjustable weights 47 by which its period of vibration may be varied. It is continuously operated by 80 means of a magnet 48 included in a vibratory circuit with contact 49. This circuit may be traced from the live pole of battery 46 through fork 45, contact 49, and the winding of magnet 48 to ground. By plucking the ends of the fork the same may be set in vibration, and as it vibrates the vibratory circuit will be alternately made and broken at contact 49 to maintain the fork vibrating. The magnet 48 is positioned between 85 the tines of the fork and its pole faces are adjacent to the same in order to draw them together when the magnet is energized, and allow them to spring apart when it is deenergized. In starting the motor C, the switch 28 is first closed 90 so as to supply direct current to the field 25 and the direct current winding of the armature. Then the fork is set vibrating and the arm 32 of the rheostat 31 is 95 manually moved until the indicator lamp 39 burns steadily. With this arrangement the source of current 46, under the control of the fork 45 and the transformer 38, supplies alternating current to the motor C, 100 and causes it to operate in part at least as a synchronous motor. This alternating current source, however, is not quite sufficient to run the motor of itself and, accordingly, the direct current source is used to supply 105 the additional energy required to properly drive the motor. Likewise, the direct current supply is used to bring the motor up to speed, in order that the same may operate synchronously with the alternating current supplied.

We may now consider the bank E of receiving relays and the associated receiving contacts F of the receiving distributor. It will be noted that the signal impulses which are applied to the conductor 20 will pass through the two windings of the line relay LR in parallel, one path leading through the artificial line 50 and the other through the line L, and the windings of the distant relay LR' and the artificial line 50' in series. Since the line relays LR and LR' are differential relays, the circuit thus traced will not operate relay LR but will operate relay 110 115 120 125 130

LR'. Likewise, if the transmitter at the distant station be employed, it will send impulses through conductor 20', dividing at relay LR', part going to ground through the artificial line 50', and the other part passing through the line L, the windings of line LR in series, and the artificial line 50 to ground. Assuming that the impulses are coming from the distant station and that the transmitter contacts 10 at that station are in the position shown, then it will be apparent that the signal receiving relays 51 of the bank E will not be operated. Thus, we may trace the path of the first impulse from positive supply main 11 through lead 13, normal contact 10, segmental contact 17, brush 18, ring contact 19; all at the distant station, then through conductor 20', line L, line relay LR, and artificial line 50 to ground. The application of current by the closing of this circuit will cause relay LR to shift its tongue 52 to the left, and this will close a circuit from battery 53 through the windings of printing relay PR to ground. Relay PR will then shift its tongue 54 to the left and thus disconnect conductor 56 and the segmental receiving contacts 55. Consequently, as the brush 57 passes over the first contact 55, no current will be applied to the first signal receiving contact 58 and, consequently, no current will flow through the first receiving magnet 51. Similarly, a circuit through the second transmitter contact 10 may be traced from the negative supply main 12 through lead 14, the second normal contact 10, the second transmitter segmental contact 17, brush 18, ring contact 19, conductor 20', line L, line relay LR, and artificial line 50 to ground. This current, being in the opposite direction, will cause relay LR to shift its tongue 52 to the right and thus complete a circuit from battery 59 through the windings of relay PR to ground. Relay PR will then shift its tongue 54 to the right and thereby disconnect conductor 60 (at this time continuous through closed switch 61) and the multiply connected contacts 62, interposed between contacts 55 in the path of travel of brush 57. Since the first contact 62 is disconnected at the time the brush 57 passes over the second contact 58, the second receiving magnet 51 will not be operated. In a similar manner, the circuits for each of the succeeding contacts 10 of the transmitter may be traced. From the tracing of these circuits we see that while the transmitter contacts are in their normal position, there is no current flow through the receiving magnets 51. However, if one of the contacts 10 be moved to its alternate position, then it will be seen that the electrical connection will be reversed relative to that just traced, and the line relay LR will move oppositely to the way just pointed out, with the result that the printing relay PR, which

exactly follows the movements of the line relay LR, will supply current to the contacts 55 or 62, as the case may be, and thus bring about an operation of the receiving magnet 51, which corresponds to the contact 10 which has been moved to its alternate position. Thus, if we assume that the first contact 10 has been moved to its alternate position, then current will flow from the negative supply main 12 through alternate contact 10, segmental contact 17, brush 18, ring contact 19, all at the distant transmitting station, conductor 20', line L, line relay LR to ground. The polarity of this current will cause relay LR to shift or hold its tongue 52 to the right and thus close a circuit for relay PR which will cause its tongue 54 to occupy the same position. Consequently, a circuit will be completed from battery 63 through tongue 54 and conductor 56, to segmental contacts 55. Then as brush 57 passes over contacts 55 and 58, the circuit will be continued through the first receiving magnet 51 and cause its operation. From the tracing of this circuit it will be apparent that when other transmitter contacts 10 are moved to their alternate positions other corresponding receiving relays 51 will be operated. The operation of these relays will, through suitable mechanism, set up the letter or symbol corresponding to the particular combination of impulses sent over the line. In addition to receiving the five signal impulses through its magnets 51, the operating magnet 64 of the receiver will receive an additional or sixth impulse through segmental contact 65, as the latter is brought by brush 66 into connection with ring contact 67 which, in turn, is connected to the live pole of battery 68. This sixth impulse operates the magnet 64 to perform some desired function in connection with the printer, such as operating the printing magnet. As shown, the contact 65 is associated with the first channel and a similar contact 65' is associated with the second channel. Similarly, the contacts 58 are associated with the first channel and contacts 58' with the second channel. The contacts 58 and 58' are short and positioned directly opposite the middle of the co-operating contacts 55 and 62, in order that they may receive current during the middle of the impulse wave in a manner which is well known in the art.

We may now consider the indicating means by which the attendant at the receiving station determines the relative speeds of the distributors at the transmitting and receiving stations. For the purpose of indicating the relative speeds, we employ lamps S and F, which are connected to contacts which lie between the several receiving contacts 58 and 58'. Lamp S is directly connected by conductor 69 with alternate indicator contacts 70. Similarly,

lamp F is connected by conductor 71 to the intermediate indicator contacts 72. Before the apparatus is in condition for transmitting signals, it is necessary to place the transmitting and receiving distributor in synchronism. If it be assumed that the correcting distributor at the transmitting station, and the distributor to be corrected at the receiving station, are being driven by their motors, then for the purpose of testing synchronism, the switches 15 and 15' at the transmitting station are closed so as to bring the transmitting contacts 10 into circuit. Then, with the contacts 10 in their normal position, as we have seen, an alternating current will be supplied to the line. The receiving of this current by the line relay LR will cause its tongue 52 to oscillate to and fro with the result that the tongue 54 of printing relay PR will partake of like movements. At the time this test is being made, the switch 61 is open and, consequently the oscillations of tongue 54 of relay PR will regularly apply current from battery 63 to conductor 56 and segmental contacts 55. Then, when brush 57 passes over these contacts, it will connect the same with indicator contacts 70 and 72 successively. In some instances, dependent upon the time the incoming impulses are received relative to the time the brush 57 bridges these contacts, the lamps S and F will be connected in circuit. The operation of these will be more clearly understood upon reference to Fig. 5 wherein seven circuit conditions are depicted. In each of the diagrams the lines 73 represent the current impulses which come in over the line and are applied to the relays LR and PR. In the first diagram the incoming impulses agree exactly with the segments 55. In other words, the first impulse begins to arrive just as the brush first engages segment 55. This means that while the brush is passing over the segment, current will be applied to it. The extent of application of current is indicated by shading that portion of the contact which is receiving current. Thus, if we look at the second diagram, we will see that the impulse arrives just at the moment the brush is leaving the first segment 70. This means that the current will be applied while the brush passes over the shaded portion of the contact 55 of this diagram. It will be remembered that contacts 62 are disconnected by reason of the open switch 61, and, consequently, even though the impulse continues while the brush is passing over a portion of segment 62, as shown in the second diagram, still no current flows through that segment because of its open circuit condition. Similarly, in the other diagrams, the shaded portions indicate the duration of application of current to the segmental contacts. Now, with current applied as shown in the first diagram, it will be seen that a circuit will be completed through both lamps S and F. In the second diagram, only the lamp F will be lighted. This is true for the reason that the brush does not engage contact 70 at the time the current is being supplied to it. In the third diagram, we have the condition in which the impulse of current begins at the instant the brush first engages contact 72. Under this condition, the lamp F is also lighted. In the fourth diagram, the impulse of current coincides with the segment 62, and as these are disconnected, no current is applied to the lamps and both are extinguished. In the fifth diagram, the impulse again overlaps contact 55 and current is supplied to light lamp S alone. In the sixth diagram, the current impulse still further overlaps the segment 55, but not segment 72. Again only lamp S is lighted. In the seventh diagram, the incoming impulse again coincides with segment 55, and the first condition is repeated, and both lamps S and F are lighted. In the case assumed, the impulses have been coming in at a given rate, and the receiving distributor has been going at a rate too fast to match its contacts 55 with the incoming impulses. This is indicated by the fact that the lamp F is the last to go out. By reference to the diagrams of Fig. 5, it will be seen that both lamps are lighted; then S is extinguished and F remains lighted; then both are extinguished; then S is lighted and F remains extinguished; and then both are lighted. That the receiving distributor is traveling faster than the transmitting distributor is indicated by the fact that after both lamps have been lighted, the lamp F is the last to be extinguished. When the receiving distributor is traveling slower than the transmitting distributor, then after both lamps are illuminated, the lamp F will be the first to be extinguished and the lamp S will be the last to be extinguished.

We may now consider the receiving distributor motor G and the associate controlling mechanism H. This motor and its controlling mechanism are the same in construction and arrangement as in the case of the motor C and its control mechanism D. It will, therefore, be unnecessary to give a further description, but for convenience of reference the various parts are designated by similar but primed characters. The controlling fork 45', however, is subject to additional control. In operation, the transmitter fork 45 is the correcting element while the receiver fork 45' is the corrected element. The additional controlling means for fork 45' include an electromagnet 74, having its windings in circuit with a resistance 75 and the variable resistance 76 of a rheostat 77, the adjustable arm 78 of which

is normally connected by conductor 79 to the left hand contact of holding relay HR, the tongue 80 of which is connected to the live pole of battery 81. A switch 82 in the conductor 79 serves to provide an alternate path through conductor 83 directly to the battery 81. As illustrated more particularly in Figs. 6 and 7, the magnet 74 is preferably structurally divided, one-half comprising winding 83 and magnetic core 84 lying above the tines of the fork 45', and the other half comprising the winding 85 and the magnetic core 86 lying below the tines of the fork. These parts are so located that the polar faces of the cores 84 and 86 come into close proximity to the edges of the tines of the fork. A switch 87 and connections 88' serve to open and close a shunt around the resistance 75. The magnet 74 is normally under the control of the holding relay HR and operates when energized, to exert its influence upon the tines of the fork 45'. This normal condition exists when the switch 82 occupies its left hand position. For the purpose of starting, it is desirable to supply the magnet 74 with continuous current, and this is obtained when the switch 82 is moved to its right hand position. A further control of the fork 45' is provided by an electromagnet 88 which is connected by conductor 89 to the resistance 90 of rheostat I, the arm 91 of which is connected to the live pole of grounded battery 92. As shown more particularly in Figs. 6 and 7, the magnet 88 includes two windings 93, 94, mounted upon a U-shaped core 95, the ends of which are in line with the ends of the tines of the fork. The position of this magnet may be varied with reference to the ends of the tines by means of an adjusting screw 96 which passes through a solid post 97. The screw 96 is threaded through a threaded opening in the post 97, and is suitably connected to the yoke 95, so that the latter may be shifted to and fro by turning the screw 96. By this screw an approximate adjustment may be obtained by hand. A continuous adjustment is obtained electrically by varying the current flow through the windings of the magnet 88. The variable current flow is brought about by varying the position of the rheostat arm 91. At this point it may be noted that this arm is frictionally mounted upon its shaft 98 so that it may be moved by hand by overcoming the frictional resistance. When not operated by hand it is rotated by its shaft 98, which is connected by a train of gears 99 to the shaft 100 of the motor 101, which is supplied with current from supply mains 102, 103. The train of gearing 99 is such that the arm 91 is driven at a very low speed. In practice we have found that a ratio of 3000 to 1 between the shafts 100 and 98 gives satisfactory results. The motor 101 is under the control of motor relay MR, and is arranged so that the direction of current flow through its armature may be reversed by said relay. At all times current flows through the field winding 104 in the same direction. The path for this current may be traced from supply main 102 through resistance 105, resistance 106, and the field winding 104, to supply main 103. When the tongue 107 of the motor relay MR is in its right hand position, current will flow downward through the motor armature over a path which may be traced from main 102 through resistance 105, the motor armature, right hand contact 107, and field winding 104, to main 103. When the tongue 107 of relay MR is in its left hand position, then current will flow upward through the armature of the motor over a path which may be traced from main 102 through left hand contact 107, the armature of the motor, resistance 106, and field winding 104, to supply main 103. Thus we see that the receiving distributor fork is under the control of two magnets which in turn are under the control of relays HR and MR, the former connecting its magnet 74 into circuit intermittently, and the latter causing the current through its magnet 88 to vary continuously, either to cause a speeding up of the fork vibrations or a slowing down of the same. In this connection it may be noted that when either of these magnets is energized, a magnetic flux is set up, and the effect of this magnetic flux upon the tines of the fork is to increase their rate of vibration.

We may now refer to the correction of the receiving distributor. This is brought about through correcting segmental contacts upon the receiving distributor head which variously operate switching relay SR and correcting relay CR to bring about an operation of relays HR and MR, to apply the correcting influences of the magnets 74 and 88. The correcting contacts upon the distributor head include a series of contacts 108 which are connected by conductor 109 through relay SR to ground. They also include a series of contacts 110 which are connected by conductor 111 to one side of a condenser 112, the opposite side of the condenser being connected by conductor 113 to the tongue 114 of relay SR. The correcting contacts 108 and 110 are connected to the ring contact 115 by a brush 116, and the contact 115 is connected by conductor 117 to the tongue 52 of the line relay LR. From this it will be seen that as the line relay is operated, it will apply current to the correcting contacts 108 and 110 through ring contact 115 and brush 116. The current will be applied in this way as the signal impulses are being received. The arrangement is such that two adjacent contacts 108

and 110 have an aggregate length corresponding to the duration of one signal impulse, and so long as the current applied to both segments is the same in polarity no correction is made, but whenever the current is reversed during the passage of the brush over such a pair of contacts, correction is made. Thus, the energy for correcting is obtained from the signal impulses themselves and an extra correcting impulse is not required. The operation will be readily seen if we assume a case. Thus, if the correcting and corrected distributors are running in synchronism, then no correction will be applied. In such case, reversals will come between the pairs of correcting contacts and a reversal will not occur while the brush is at any other position. If we are sending a signal which requires the first contact 10 to be in its normal position, the second contact 10 to be in its normal position, the third contact 10 to be in its alternate position, and the fourth contact 10 to be in its alternate position, then it will be seen that the tongue 52 of relay LR will occupy its left hand position during the first impulse, its right hand position during the second and third impulses, and its left hand position during the fourth impulse. As there is exact synchronism, the brush 116 will pass over the first pair of contacts 108 and 110 while tongue 52 of relay LR closes its left hand contact and thus applies positive battery to the contacts. Likewise, while the brush 116 is passing over the second and third pairs of correcting contacts 108, 110, the tongue 52 of relay LR will apply negative battery to those contacts, and again while the brush passes over the fourth pair of contacts 108 and 110, the tongue 52 will apply positive currents to those contacts. Now, the effect of such application of current to these correcting contacts can be readily seen. The application of positive current to the first contact 108 will complete a circuit through conductor 109 and the windings of switch relay SR to ground. This will cause the tongue 114 of relay SR to remain in or move to its right hand position. The continued application of positive current to the correcting contact 110 of the first pair will cause one side of condenser 112 to be charged with positive current. Charging the condenser in this way will induce a negative charge upon the opposite side of the condenser, resulting in a flow of current through the right hand winding of correcting relay CR. The effect of negative current in the right hand winding is to cause tongue 118 of relay CR to remain in or move its right hand position. At this point it may be noted that the same effect will be produced by the passage of positive current through the left hand winding. Likewise, positive current through the right

hand winding or negative current through the left hand winding will cause tongue 118 to move to its left hand position. Since, in our assumed case, tongue 118 lies in its right hand position, a circuit will be completed for the right hand windings of motor relay MR and holding relay HR. This circuit may be traced from the live pole of battery 68 through ring contact 67, brush 66, contact 119, conductor 120, right hand contact 118, the right hand winding of relay MR, and the right hand winding of relay HR to ground. By reason of the four contacts 119, this circuit may be completed four times for each revolution of the receiving distributor. Consequently, correction is not applied immediately upon the finding of a condition requiring correction, but only when a contact 119 is brought into circuit. In this instance the closing of circuit 85 through the right hand windings of relays MR and HR has the effect of holding the tongues 107 and 80 in or moving them to their right hand positions. In the right hand position of tongue 80, no circuit 96 is completed for magnet 74 and, consequently, no correction is applied through this magnet. With tongue 107 of relay MR in its right hand position, the flow of current through the motor 101 is such as to 95 rotate the rheostat arm 91 in a direction to increase the amount of resistance 90 in circuit and, therefore, reduce the magnetic flux in electromagnet 88 and permit the fork 45° to slow down its vibration. Now, when we come to a consideration of the second pair of correcting contacts 108, 110, we find under the assumption, that the second transmitter contact 10 is in its normal position, and therefore relay LR is operated to move 105 its tongue 52 to its right hand position to apply negative current through conductor 117, ring contact 115, and brush 116, to the second pair of contacts 108, 110. The application of negative current to the contact 108 of this pair causes a flow of current through conductor 109 and the windings of relay SR. This flow results in causing tongue 114 of the latter relay to move to 110 its left hand position. The application of negative current to the contact 110 of the second pair results in charging the adjacent side of the condenser with a negative charge. This induces a positive charge upon the opposite side of the condenser, and the current flowing through the left hand winding of relay CR and the left hand contact 114 at such time, causes tongue 118 of relay CR to remain in its right hand position, 115 with the same effect upon relays MR and HR as just described. In other words, no correction is applied as a result of this condition. Coming now to the third pair of contacts 108, 110, we find the third transmitter contact 10 in its alternate position, 120 125 130

and the application of negative current to the correcting contacts 108, 110 of the third pair, just as in the case of the second pair. The application of this current to contact 108 of this pair causes a flow of current through conductor 109 and the windings of relay SR, just as before, and the tongue 114 of that relay remains in its left hand position. At this time, however, the condenser 112 is already charged and has not been discharged since charged over the contact 110 of the second pair of contacts and, consequently, there is no flow of current for the third impulse through the left hand winding of relay CR. Again, the effect upon relays MR and HR is the same as before described and there is no correction applied. Coming now to the fourth impulse, we have positive current applied, according to our assumption, to the contacts 108, 110 of the fourth pair of correcting contacts. The effect of this application of current upon relays SR, CR, MR, and HR, is the same as described in connection with the first impulse, and the first pair of correcting contacts 108, 110. Again, there is no correction applied. From these considerations, it will be clear that so long as the reversals between impulses occur between the pairs of correcting contacts, there is no application of a correcting influence. This condition will, of course, exist only when the correcting and corrected distributers are running in synchronism, or so close thereto that a change of polarity between pulses occurs at the instant the brush 116 is passing from the second contact of one pair to the first contact of the next pair.

If, now, we assume that the two distributers are not in synchronism, then the change in polarity will not occur between the pairs of correcting contacts 108, 110, but will occur while the brush 116 is in engagement with one of these contacts. Thus, if it be assumed that we are transmitting the same signal as before, viz: The first impulse positive, the second and third negative, and the fourth positive, and that the change in polarity between the first impulse and the second impulse occurs at the time the brush is on contact 110 of the first pair of correcting contacts, then we will see that the relays are operated to apply correction in a way not heretofore done. Under this assumption, the positive current supplied to contact 108 will energize relay SR to move its tongue 114 to its right hand position just as heretofore described. The application of positive current to the first pair of correcting contact 110 will charge the adjacent side of the condenser 112 positively, and negative current will flow to charge the other side of the condenser through the right hand winding of relay CR, and this will result in maintaining the contact 118 in its right hand position. The resulting application of current through the right hand windings of relays MR and HR will be the same as heretofore noted, and no correction will be applied. But, under the assumption, brush 116 does not disengage contacts 110 until the polarity of the current is changed by the advent of the second impulse. This means that while the tongue 114 of relay SR remains in its right hand position, the condenser 112 is charged negatively, and a positive current flows through the right hand winding of relay CR. This current, as above noted, causes tongue 118 to move to its left hand position. Therefore, as soon as brush 66 connects contact 119 to battery 68, there will be a flow of current through the left hand windings of relays MR and HR, with the resulting movement of the tongues 107 and 80 to their left hand positions. Tongue 80 will apply current from battery 81 through conductor 79 and rheostat 77 to controlling magnet 74. This application of current will set up a magnetic flux which will cause the speed of the fork 45' to increase. This will tend to cause the motor G to increase its speed and, therefore, cause the brush 116 to catch up to the incoming impulses. This action of the fork is increased by the reversal of connections of the motor 101 through tongue 107 of relay MR and, as a consequence, rheostat I is operated to gradually cut out resistance 90 from the circuit of magnet 88. This, as before noted, has the effect of increasing the speed of the fork. From what we have said it will be seen that the motor speed will continue to increase until there is another change of polarity upon one of the correcting contacts 108, 110, and when such change occurs the relays MR and HR will be operated to move their tongues to their right hand positions. In such case the motor speed will be gradually reduced until, again, the condition just described is reached, whereupon the same relays will be operated to initiate an increase in the motor speed. In this way the speed of the motor G increases and decreases continuously through a given range. In practice, the parts are so adjusted that about half of the time the motor is running fast, and the other half running slow. In this way a practical synchronism between the correcting and corrected distributers is obtained.

We may now consider the adjustment of the ring of correcting contacts 108, 110. In practice, it is found necessary, due to characteristics of the instruments, to provide for a relative adjustment for the correcting contacts 108, 110, and the receiving contacts 58, 58'. In some instances in the prior art, the signal receiving contacts have been adjusted relative to all the other contacts upon the receiving distributor head, but this arrangement required a new positioning of the

operating or sixth pulse contacts, which resulted in objectionable operation. We find, on the other hand, that by adjusting the ring containing correcting contacts 108, 110, relative to the other contacts of the distributor head, satisfactory results may be obtained. In Figs. 2, 3 and 4, we have shown a preferred construction for bringing about this adjustment of these contacts. In those figures, the rings of contacts are differently arranged than in the diagram of Fig. 1. In the latter figure, rings have been placed side by side for convenience of illustration. In the structural figures the contacts are arranged as they are in practice, and each brush spans two rings of contacts and the brushes are positioned 120 degrees apart as clearly shown in Fig. 2. In the preferred structure, all contacts except the correcting contacts 108, 110 are mounted upon an insulating disc 124 which is suitably secured by bolts 125 and spacing washers 126 to the casing 127 which, in turn, is provided with a base 128 by which it may be secured to any suitable support. The correcting contacts 108, 110 are preferably secured to an insulating ring 129 which closely fits upon the periphery of the disc 124. Shoulders upon the disc 124 and the ring 129 abut at 130 and prevent the outward withdrawal of the ring from the disc. Spring tongues 131 are secured to the rear of the disc 124 and extend outward beyond the disc and into engagement with the rear of the ring 129. By this construction the ring 129 is held in place by a frictional engagement of the parts. When it is desired to adjust the ring 129 and the correcting contacts 108, 110 carried by it, it is only necessary to manually grasp the handle 132 which is secured to the face of the ring 129 by any suitable means such as screws 133, and move the ring and its contacts against the friction of the parts until the ring is moved to its desired position, in accordance with the indication of the left hand edge 121 of the handle 132 upon a scale 134 marked upon the adjacent edge of the casing 127.

We may now consider the operation briefly. With the apparatus in a condition of rest, the first step is to start the motors at both transmitting and receiving stations. In the case of the motor C this is done, as before explained, by first closing switch 28 and bringing the motor up to speed by means of the rheostat 31. At the same time the fork 45 is set in vibration and alternating current is supplied to the motor. When the motor is operating satisfactorily the lamp 39 burns steadily. The motor G is started in the same way. The next step is to close switches 15 and 15', so as to include the transmitter contacts in circuit. Thereupon, the rotation of the transmitting distributor 65 applies a pure alternating current to the line. The next thing is to place each receiving distributor in phase with the distant transmitting distributor. To this end, switches 61 and 82 are opened. By the opening of the former, proper circuit conditions are established for the operation of the indicator lamps S and F. By the opening of the latter, control magnet 74 is prevented from operating. Magnet 88 is then adjusted until the receiving distributor runs slower than the transmitting distributor by a certain definite amount. This adjustment is obtained by manually moving the rheostat arm 91 over the resistance 90 until the desired speed is obtained. In determining the latter, speed differences are measured by the length of time intervening between successive lightings of lamp S or of lamp F and the fact that the receiving distributor runs slower than the transmitting distributor is shown by the lamp S going out last, as before explained. Having obtained the desired speed difference with correcting magnet 74 cut off, then said magnet is included in circuit and the receiving distributor is adjusted to run faster than the transmitting distributor by a certain definite amount. In making this faster speed adjustment the switch 82 is moved to its right hand position and the rheostat arm 78 is moved back and forth over resistance 76 until the desired speed difference is obtained. The fact that the receiving distributor runs faster than the transmitting distributor is indicated by lamp F being last to go out. In this instance, the period is measured by observing the lightings of one of the lamps just as before. Theoretically, the speed difference in both cases should be the same amount, and in a two channel system such as herein disclosed that difference may be in the neighborhood of .3 R. P. M. With such an assumed speed difference, which is merely illustrative, the receiving distributor should run .3 R. P. M. slower than the transmitting distributor with magnet 74 out of circuit and .3 R. P. M. faster than the transmitting distributor with magnet 74 in circuit. Measured by the interval between successive lamp lightings, this .3 R. P. M. would amount to 40 seconds. However, in practice, it is found that equal and opposite effects upon the receiving distributor cannot be had with speed differences of the same amount. We have found it necessary to reduce the speed difference when the receiving distributor is run slower than the transmitting distributor, and to increase the same when the receiving distributor is run faster than the transmitting distributor. Thus, good results have been obtained by running the receiving distributor .1 R. P. M. slower than the transmitting distributor with a magnet 74 out of circuit and .5 R. P. M. faster with magnet 74 in circuit. The difference between the theoretical and 130

practical values may be due to the difference in the action of magnet 74 when energized continuously, as it is when the above starting adjustments are being made, and when energized intermittently, as it is when adjustments are automatically made during the regular operation of the system.

The next step in the operation is to "find the letter". To this end switch 61 is closed and switch 82 is moved to its left hand position. Then the printers on all channels are turned on and the transmitting station is requested to transmit some letter, as the letter R, on one of the channels, say the first. If the printer on this channel prints the letter R continuously, while the other channel printers are at rest, the letter has been found. In case this result is not had, then switch 82 is thrown to its right hand position and switch 87 is closed. This results in energizing correcting magnet 74 with an abnormally heavy current which tends to make the fork 45' run considerably faster than usual. The result of this action of the fork is to cause the receiving distributor to gain rapidly upon the transmitting distributor until the two are in proper phase relation, as is indicated by the printing of the letter R upon the first channel printer. When the letter is thus found, switch 82 is thrown to the left hand position and switch 87 is opened. This places the system in condition for operation. During operation the signal impulses themselves bring about corrections in synchronism through the agency of the correcting contacts on the receiving distributor and the associated relays SR, CR, MR and HR in the way previously described. The signals are also sent in the manner previously explained.

With reference to the forks 45 and 45', it may be pointed out that each is provided with weights to assist in determining accurately the rate of vibration. In practice the transmitting fork 45 has its weights 47 adjusted until it vibrates at a definite rate. In like manner the fork 45' is provided with weights 47', and these are adjusted upon the fork until the latter vibrates at a somewhat less rate than the correcting fork 45. The adjustment of the magnet 88 causes the fork 45' to increase its rates but still leaves it below that of the correcting fork 45. Then when the correcting magnet 74 is brought into play, the joint effect of the two magnets 74 and 88 is such as to cause the fork 45' to vibrate at a rate slightly in excess of that of the fork 45. As before noted, it is desirable to operate the receiving fork so that about fifty per cent of the time it will be running fast, and about fifty per cent of the time running slow, relative to the fork 45 of the transmitting station.

Before concluding the description, it

should be noted that the relays LR, PR, SR, CR, MR and HR are polarized and each will hold its tongue in that position to which it was last moved until current is received which will move it to the opposite position. Relays LR and PR move their tongues to the left upon the receipt of positive current and to the right upon the receipt of negative current as indicated by the positive and negative signs upon the drawing. Relay SR is operated by positive current to move its tongue to the right and by negative current to move its tongue to the left, as indicated. Relay CR moves its tongue to the right upon receipt of positive current in the left hand winding, or negative current in the right hand winding as indicated by the positive sign above the left hand winding, the negative sign above the right hand winding and the associated arrows pointing toward the right. The reverse movement is caused by negative current in the left hand winding or positive current in the right hand winding as shown by the second row of signs and arrows. Relays MR and HR move their tongues to the left when current is received in the left hand windings and to the right when current is received in the right hand windings.

Obviously the main line L may be a complete metallic line or a line having a ground return such as illustrated. Where the latter is the case, the transmission current source must be grounded. This may be accomplished in various ways. As shown in Fig. 1, two electric generators 137 and 138 are connected in series circuit with the supply mains 11 and 12 and the ground is applied between the generators at 139.

Throughout the drawing a number of batteries appear. In practice ordinarily but one source of current would be necessary at each station. This might be a battery or other current source. The batteries illustrated are merely illustrative of sources of current supply and the many sources have been shown merely to simplify the diagram and to avoid rendering the same obscure or difficult to read.

By way of modification it may be pointed out that correcting magnet 88 may be operated by hand and without using the motor 101 and associated rheostat I. In such case, the relay MR would have no useful function and might be omitted. Where such a change is desired, the windings of magnet 88 are connected in circuit with a source of current, such as the battery 136, as indicated in the diagram by the switch 135 being thrown to its upper position. When the switch 135 is in its lower position the motor 101 and associated rheostat I are connected in circuit to perform their functions as above explained. When the relay 88 is to be manually controlled, the screw 96 is used. By

it, as previously explained, the position of the magnet may be carefully adjusted relative to the tines of the fork 45'. In practice, where the motor 101 and associated rheostat I are omitted, repeated manual adjustment is necessary to keep the parts running properly. By the provision of the motor and rheostat, the necessity of this constant attention is done away with.

As a further modification of the structure, it should be kept in mind that distributors of other types than those employing segmental contacts and co-operating brushes may be employed. Thus we may locate pairs of contacts adjacent to each other and move them into and out of contact by means of a rotating drum, or other traveling member.

As previously pointed out, the system may be further modified by adapting it for use in transmitting signals by radiant energy through the air, ether, or other agency than a telegraph wire.

Obviously too the tuning forks 45 and 45' might be replaced by other vibrating members. However, forks are ordinarily preferred because they can be properly operated when mounted on relatively light bases whereas reeds and other similar vibrating members having only one vibrating element require a very rigid supporting base.

Other modifications will readily suggest themselves to persons skilled in the art. In view of these obvious changes I, therefore, do not wish to be limited to the specific matter herein disclosed, but aim to cover all such modifications by the terms of the appended claims.

What I claim and desire to secure by Letters Patent of the United States is

1. A system of the class described including means for transmitting signals by current variations, a distributor, a motor for driving said distributor, a vibrating member and connections for controlling said motor, means responsive to said current variations for exercising control of said vibrating member by intermittent action, and means also responsive to said current variations for exercising an additional control of said vibrating member by a continuous variable action.

2. A system of the class described including means for transmitting signals by current variations, a distributor, a motor for driving said distributor, a vibrating member and connections for controlling said motor, an electromagnet for controlling said vibrating member, a relay and connections responsive to said current variations to energize and deenergize said electromagnet, a second electromagnet for controlling said vibrating member, and means for continuously energizing said second electromagnet by a variable current.

3. A system of the class described includ-

ing independently driven correcting and corrected distributors, adjustable regulating means operable in one condition to apply a force tending to cause the corrected distributor to run slightly faster than the correcting distributor and in another condition to apply a different force tending to cause the corrected distributor to run slightly slower than the correcting distributor, and means responsive to impulses from the correcting distributor to operate said regulating means to vary both said forces in the maintaining of synchronous operation.

4. A system of the class described including independently driven correcting and corrected distributors, means for applying two correcting forces both operative to increase or decrease the speed of the corrected distributor relative to that of the correcting distributor, and means responsive to signaling impulses from the correcting distributor for varying both of said forces in the maintaining of synchronous operation.

5. The combination of an electromagnetically operated vibrating member, means for varying the rate of vibration of said member by an intermittent action and also by a continuously variable action.

6. The combination of an electromagnetically operated vibrating member, an electromagnet for controlling the variations of said member, means for energizing said electromagnet intermittently, a second electromagnet for controlling the vibrations of said member, and means for energizing said second electromagnet continuously by a more or less fluctuating current.

7. A system of the class described including means for transmitting signals by current variations, a distributor, a motor for driving said distributor, a vibrating member and connections for controlling said motor, two electromagnets for variably controlling the rate of vibration of said member, relay means responsive to said current variations, and means for causing said electromagnets to operate cumulatively for one condition only of said relay means.

8. A system of the class described including means for transmitting signals by current variations, a distributor, a motor for driving said distributor, a vibrating member and connections for controlling said motor, two electromagnets for variably controlling the rate of vibration of said member, relay means responsive to said current variations, and means responsive to one condition of said relay means to cause said electromagnets to operate cumulatively with a gradually increasing effect.

9. A system of the class described including means for transmitting signals by current variations, a distributor, a motor for driving said distributor, a vibrating member and connections for controlling said motor,

two electromagnets for controlling said vibrating member, relay means responsive to said current variations, and means for causing said electromagnets to act cumulatively only for one condition of said relay means and only one of said electromagnets to act for another condition of said relay means.

10. A system of the class described including means for transmitting signals by current variations, a distributor, a motor for driving said distributor, a vibrating member and connections for controlling said motor, two electromagnets for controlling said vibrating member, relay means responsive to said current variations, and means responsive to one condition of said relay means to cause said electromagnets to act cumulatively with a gradually increasing effect and responsive to another condition of said relay means to cause the joint effect of said electromagnets to be less and gradually decreasing.

11. A system of the class described including means for transmitting signals by current variations, a distributor, a motor for driving said distributor, a vibrating member and connections for controlling said motor, two electromagnets for controlling said vibrating member, relay means responsive to said current variations, and means responsive to one condition of said relay means to cause said electromagnets to act cumulatively with a gradually increasing effect and responsive to another condition of said relay means to cut one of said electromagnets out of circuit and cause the other to act with a gradually decreasing effect.

12. The combination of a vibrating member, means for influencing the period of vibration of said member, an arm movable to and fro at a slow speed to control said influencing means, and a reversible motor for actuating said arm.

13. The combination of a vibrating member, electromagnetically controlled means for influencing the period of vibration of said member, a rheostat included in circuit with said means, a motor geared to the arm of said rheostat so as to move the same to and fro over the rheostat resistance at a slow speed, to vary the influence of said influencing means, and means for reversing said motor.

14. The combination of a traveling member, means for influencing its speed of travel, and an arm continuously driven at a slow speed to control said influencing means.

15. The combination of a traveling member, means for influencing the speed of travel of said member, an arm movable to and fro at a slow speed to control said influencing means, and a reversible motor for actuating said arm.

16. The combination of a traveling member, electromagnetically controlled means

for influencing the speed of travel of said member, a rheostat included in circuit with said means, a motor geared to the arm of said rheostat so as to move the same to and fro over the rheostat resistance at a slow speed to vary the influence of said influencing means, and means for reversing said motor.

17. A system of the class described including a conductor, means for transmitting signals over said conductor by current variations, a distributor, a motor for driving said distributor, a vibrating member and connections for controlling said motor, an electromagnet for controlling said vibrating member, a circuit for said electromagnet, a relay under the control of said conductor for controlling said circuit, a second electromagnet for controlling said vibrating member, a circuit for said second electromagnet, a variable resistance in said latter circuit, and means under the control of said relay for varying the amount of said resistance included in said circuit.

18. A system of the class described including a conductor, means for transmitting signals over said conductor by current variations, a distributor, a motor for driving said distributor, a vibrating member and connections for controlling said motor, an electromagnet for controlling said vibrating member, means under control of said conductor for intermittently energizing said electromagnet, a second electromagnet for controlling said vibrating member, a rheostat and current supply connected in circuit with said second electromagnet, a motor geared to operate the rheostat arm continuously at a very low speed, and means under control of said conductor for determining the direction of rotation of said motor and said rheostat arm.

19. A system of the class described including a conductor, means for transmitting signals over said conductor by current variations, a distributor, a motor for driving said distributor, a vibrating member for controlling said motor, and means responsive to current variations in said conductor and continuously operative to gradually increase or gradually decrease the rate of vibration of said member.

20. A system of the class described including a conductor, means for transmitting signals over said conductor by current variations, a distributor, a motor for driving said distributor, a vibrating member for controlling said motor, an electromagnet for controlling the vibrations of said vibrating member, and means responsive to current variations in said conductor to continuously energize said electromagnet by a variable current.

21. A system of the class described including a conductor, means for transmitting

signals over said conductor by current variations, a distributer, a motor for driving said distributer, a vibrating member for controlling said motor, an electromagnet for controlling the vibrations of said vibrating member, a resistance adapted to be included in circuit with said electromagnet, means for varying the resistance included in said circuit, and means responsive to current variations in said conductor to control said resistance varying means.

22. A system of the class described including a conductor, means for transmitting signals over said conductor by current variations, a distributer, a motor for driving said distributer, a vibrating member for controlling said motor, an electromagnet for controlling the vibrations of said vibrating member, a rheostat and current supply connected in circuit with said electromagnet, a motor geared to operate the rheostat arm continuously at a very low speed, and means responsive to current variations in said conductor to determine the direction of rotation of said motor and rheostat arm.

23. A system of the class described including a conductor, means for transmitting signals over said conductor by current variations, a distributer, a motor for driving said distributer, a vibrating member to determine the speed of said motor, a relay responsive to current variations in said conductor, and means operative in one position of said relay to gradually increase the speed of said vibrating member and in another position of said relay to gradually decrease the speed of said vibrating member.

24. A system of the class described including a conductor, means for transmitting signals over said conductor by varying current impulses according to combinations of a code having the same number of time intervals for each signal, a receiving distributer having passive correcting contacts and traveling means for successively closing circuit with said contacts, an electric motor for driving said distributer, means for regulating the motor speed so that the distance traveled by said traveling means during each time interval of the signal shall approximate that required to close circuit with two correcting contacts, controlling means acting continuously upon said motor and tending to vary its speed, and means dependent upon the electrical condition of said correcting contacts to vary the operation of said controlling means.

25. A system of the class described including a conductor, means for transmitting signals over said conductor by varying current impulses according to combinations of a code having the same number of time intervals for each signal, a receiving distributer having passive connecting contacts and traveling means for successively closing cir-

cuit with said contacts, an electric motor for driving said distributer, means for regulating the motor speed so that the distance traveled by said traveling means during each time interval of the signal shall approximate that required to close circuit with two correcting contacts, additional means for further controlling the motor speed, an electromagnet for controlling said additional means, a rheostat and source of current in circuit with said electromagnet, a motor for driving the rheostat arm to and fro continuously at a very low speed, means for reversing said latter motor, and means dependent upon the electrical condition of said correcting contact to cause the operation of said reversing means.

26. A system of the class described including transmitting and receiving distributers, means for sending signals from the former distributer to the latter by varying current impulses according to a code having the same number of time intervals for each signal, electric motors for driving said distributers, means for driving said motors at approximately the same speed, and means for maintaining synchronism between said distributers including means independent of said driving means for continuously acting upon the receiving motor and tending to change its speed and means dependent upon the energy of the signal impulses themselves to vary the operation of said changing means.

27. A system of the class described including transmitting and receiving distributers, means for sending signals from the former distributer to the latter by varying current impulses according to a code having the same number of time intervals for each signal, electric motors for driving said distributers, means for bringing said motors up to approximately the same speed, and means for maintaining synchronism between said distributers including additional means for further controlling the receiving motor speed, an electromagnet for controlling said additional means, a rheostat and source of current in circuit with said electromagnet, a motor for driving the rheostat arm to and fro at a very low speed, means for reversing said latter motor, and means dependent upon the energy of the signal impulses themselves to cause the operation of said reversing means.

28. A system of the class described including independently driven correcting and corrected distributers, means located at the corrected distributer and controlled by impulses from the correcting distributer, for determining the relative speeds of said distributers, two adjustable regulating means operable in one condition to cause the corrected distributer to run slightly faster than the correcting distributer and in another

condition to cause the corrected distributor to run slightly slower than the correcting distributor, and means responsive to impulses from the correcting distributor to adjust both said regulating means to maintain synchronization between said distributors.

29. A system of the class described including independently driven correcting and corrected distributors, two electric speed indicators, separate contact means controlled respectively by the corrected distributor and by impulses from the correcting distributor and co-operating to energize said electric indicators simultaneously but in different order in accordance with the relatively faster or slower speed of the corrected distributor.

30. A system of the class described including independently driven correcting and corrected distributors, the latter having separate signal receiving and indicating contacts, two electric signals connected to said indicating contacts, and means cooperating with said indicating contacts to display both of said signals in one way when the corrected distributor runs faster than the correcting distributor and in another way when it runs slower, and means for adjusting the speed of the corrected distributor to correspond with the speed of the correcting distributor.

31. A system of the class described including independently driven correcting and corrected distributors, the latter having two series of contacts, an electric signal in circuit with alternate contacts of one of said series, a second electric signal in circuit with the intermediate contacts of the same series, means for applying to the contacts of the other of said series current impulses received from the correcting distributor, traveling means for electrically connecting contacts of the two series, and means for driving said traveling means whereby the relative speeds of said distributors will be made known by said signals.

32. A system of the class described including independently driven correcting and corrected distributors, the latter having two series of contacts, each contact of the second series being adapted to engage two contacts of the first series, fast and slow indicating lamps, the fast lamp being in circuit with alternate contacts of the first series and the slow lamp being in circuit with the intermediate contacts of the same series, means for applying to the contacts of the second series current impulses received from the correcting distributor, traveling means for electrically connecting cooperating contacts of the two series, and means for driving said traveling means whereby said signals indicate the relative speeds of said distributors.

33. A system of the class described including independently driven correcting and cor-

rected distributors, the latter having alternate indicator and signal contacts arranged in a series and traveling means for successively closing circuit with said contacts, indicating means in circuit with said indicator contacts, signal elements in circuit with said signal contacts, means for applying impulses received from said correcting distributor to said contacts as said traveling means operates, to determine synchronization between said distributors by the operation of said indicating means and to receive a signal by the operation of said signal elements.

34. A system of the class described including correcting and corrected distributors, the latter having two series of contacts, one series consisting of alternate signal and indicator contacts, a series of signal receiving elements connected to said signal contacts respectively, an indicator connected to alternate indicator contacts, a second indicator connected to the intermediate indicator contacts, one electrical connection to alternate contacts of the second series, another electrical connection to the intermediate contacts of the second series, means for applying impulses received from the correcting distributor to said electrical connections, means for interrupting one of said electrical connections while determining the relative speeds of said distributors by said indicators, and traveling means for electrically connecting contacts of the two series.

35. A system of the class described including a conductor, a receiving distributor having a series of correcting contacts and a series of signal-receiving contacts, the latter followed by an operating contact having a permanent positional relation to said signal receiving contacts, means for transmitting code signals over said conductor, each signal having time intervals corresponding in number to said signal-receiving contacts, a motor for driving said distributor, means dependent upon said correcting contacts and upon energy received from the signal impulses themselves to vary the motor speed, and means for adjusting said correcting contacts as a whole relative to said signal-receiving and operating contacts as a whole.

36. A system of the class described including independently driven correcting and corrected distributors, the latter having a series of correcting contacts and a series of signal-receiving contacts followed by an operating contact having a permanent positional relation to said signal-receiving contacts, means dependent upon said correcting contacts and upon the energy of the impulses constituting the signals to vary the speed of the corrected distributor, and means for adjusting said correcting contacts relative to said signal receiving and operating contacts.

37. A system of the class described including transmitting and receiving distributers each having a plurality of channels, driving means for said distributers, a set of transmitting contacts for each channel, 5 connecting and current supply means for said contacts whereby when running idly an alternating current is transmitted through the transmitting distributer, correcting means responsive to said alternating current to change the relative speeds of said distributers, indicators, means for modifying said normal current, and means responsive to said modified current to operate 10 said indicators to indicate the relative speeds of said distributers. 15
38. A system of the class described including transmitting and receiving distributers each having a plurality of channels, driving means for said distributers, a set of code signal transmitting contacts for each channel, the number of contacts in each set equalling the number of signal intervals in the employed code, connecting and current supply means for said contacts whereby 20 when running idly plural reversals of current polarity occur in each channel, correcting means responsive to said reversals to change the relative speeds of said distributers, means for modifying said current to provide a current having regular polarity changes, indicators, and means for operating 25 said indicators in response to said modified current. 30
39. A system of the class described including transmitting and receiving distributers each having a plurality of channels, driving means for said distributers, a set of transmitting contacts for each channel, correcting and current supply means for said contacts whereby when running idly plural reversals of polarity occur in the blank signals being transmitted through each channel, 40 correcting means responsive to such normal current to change the relative speeds of said distributers, means for modifying said normal current, and speed indicating means responsive to said modified current. 45
40. A synchronous telegraph system comprising independently driven, current impulse sending and receiving distributors, operating electric motors therefor, independent vibrating members for applying periodically varying, correcting current to the windings of said motors respectively to determine the speeds of said distributers, 50 adjustable means independent of said vibrating members for driving the motors at approximately the speeds of the corresponding members, and electro-magnetic correcting means responsive to impulses imparted by the sending distributor for varying the speed of the vibrating member of the receiving distributor. 60
41. In a synchronous telegraph system, 65 independently driven, current impulse sending and receiving distributors, an electric motor for operating said receiving distributor, means for driving the motor, a synchronizing vibrating member independent of 70 said driving means and arranged to apply alternating correcting current to a winding of said motor, and correcting devices controlled by impulses imparted by the sending distributor for varying the frequency of said 75 vibrating member. 80
42. In a synchronous telegraph system, independently driven, current impulse sending and receiving distributors, operating electric motors therefor, independent electro-magnetically operated tuning forks for supplying alternating correcting current to windings of said motors respectively, adjustable means independent of said forks for driving the motors at approximately the 85 speeds of the respective forks and correcting devices controlled by impulses imparted by the sending distributor for varying the speed of the receiving distributor fork. 90
43. A system of the class described including independently driven correcting and corrected distributors, vibrating members for determining the speeds of said distributors, means for applying two correcting forces to vary the speed of vibrating member of the 95 corrected distributor relative to that of the correcting distributor, and means responsive to impulses from the correcting distributor for varying both of said forces in the maintaining of synchronous operation. 100
44. In a synchronous telegraph system employing a definite interval signal code, sending and receiving distributors, the receiving distributor having receiving and correcting contacts and a rotary member for engaging one of said receiving contacts and successively engaging two correcting contacts during each signal interval, a line relay and separate correcting and adjusting devices for said rotary member controlled by the joint operation of said line relay and said 105 correcting contacts, said correcting device acting to apply and remove a correction of predetermined value at substantially regular intervals during normal operation, and said adjusting device acting in response to abnormal conditions to gradually increase or decrease the speed of said rotary member. 110
45. In a synchronous telegraph system, the combination with independently driven correcting and corrected distributors and vibratory members for determining the speed of said distributors, of intermittently acting correcting means for applying a correction of predetermined value to the corrected distributor and adjusting means for continuously applying a correction of variable value to control the speed of the vibratory member associated with the corrected distributor, said correcting and adjusting means be- 120 125

ing automatically responsive to variations in the speeds of said distributors.

46. In a synchronous telegraph system, independently driven correcting and corrected distributors, vibrating members for respectively determining the speeds of said distributors and correcting and adjusting devices for the vibrating member of the corrected distributor and automatically controlled by the difference in speeds of said distributors, said correcting device being arranged to periodically increase or decrease the speed of the vibrating member by a definite amount and said adjusting device being arranged to gradually vary the speed of the vibrating member through a considerable range.

47. In a synchronous telegraph system, independently driven correcting and corrected distributors, vibrating members for respectively determining the speeds of said distributors, correcting and adjusting magnets applied to the vibrating member of the corrected distributor, means for intermittently energizing the correcting magnet to increase or decrease the speed of the distributor by a definite amount and means for gradually varying the flow of current through the adjusting magnet to correspondingly vary the speed of the vibrating member through a considerable range.

48. In a synchronous telegraph system correcting and corrected distributors, two indicating electric signals associated with the corrected distributor, contact means controlled by impulses received from the correcting distributor for simultaneously opening and closing the circuits of both of said signals and means controlled by the corrected distributor for alternately and at regular intervals opening and closing the circuits of said signals, whereby both of said signals operate successively in one order when the speed of the corrected distributor is faster than that of the correcting distributor and in reverse order when the speed of the corrected distributor is slower.

49. In a synchronous telegraph system, sending and receiving current impulse distributors, a motor for driving said receiving distributor, a vibrating member for determining the speed of said motor, an electro-magnet for adjusting the rate of vibration of said member, a rheostat interposed in the energizing circuit of said electro-magnet, an auxiliary control motor having speed reducing gear connections with the arm of said rheostat and means responsive to abnormal variations in the speeds of said distributors for determining the direction of rotation of said motor and the rheostat arm operated thereby.

50. In a synchronous telegraph system employing a definite interval signal code, sending and receiving distributors, the re-

ceiving distributor having receiving and correcting contacts and a rotary member for successively engaging said contacts, an electric motor for driving said rotary member, means for regulating the motor speed so that said rotary member engages two correcting contacts during each signal interval, electro-magnetic controlling means acting continuously upon said member and tending to vary its speed, and a line relay and means jointly controlled by the line relay and said correcting contacts to vary the operation of said electro-magnetic controlling means.

51. In a synchronous telegraph system employing a definite interval signal code, sending and receiving distributors, the receiving distributor having separate sets of code receiving and speed indicating contacts, and a rotary member for successively operating said indicating contacts at regular intervals proportional to the signal intervals, a line relay and two indicators controlled jointly by said indicating contacts and said line relay and thereby operated intermittently and successively in one order when the speed of the receiving distributor is faster than that of the sending distributor and in reverse order when the speed of the receiving distributor is slower.
